UNITED STATES PATENT OFFICE.

FRED F. BURDICK AND FRITZ ARTHUR ANDERSON, OF MILTON, WISCONSIN.

THERAPEUTIC VAPOR-LAMP APPLIANCE.

1,402,396.

Specification of Letters Patent. Patented Jan. 3, 1922.

Application filed April 15, 1920. Serial No. 374,139.

To all whom it may concern:

Be it known that we, FRED F. BURDICK and FRITZ A. ANDERSON, citizens of the United States of America, and residents of 5 Milton, county of Rock, and State of Wisconsin, have invented certain new and useful Improvements in Therapeutic Vapor-Lamp Appliances, of which the following is a specification.

10 This invention relates to radio-therapeutic appliances. The main objects of the invention are to provide an improved form of lamp support and casing; to provide an improved form of controlling means for the 15 ray generator or lamp proper, adapted especially for mercury vapor lamps; to provide an improved method and means for adjusting the casing, adapted to facilitate better and more efficient control and direction of 20 the rays; to provide for effective ventilation and cooling of the device, especially where large and powerful lamps are to be used; to provide a casing of jointed sectional form adapted for variable adjustment with ready 25 means for operation and control, and with relative sliding movement of the wall members past one another for adjusting the aperture of the ray opening; to provide in the 30 casing adjustable means for collecting and reflecting the otherwise ineffective rays and directing them forward in a common beam with the direct rays; to provide manual means of improved form adapted for ready 35 operation to adjust the ray aperture, the reflector, and the position of the generator respectively, from outside the casing; to provide in connection with said casing an improved form of attachment, for use when desired, adapted for concentrating and 40 conducting the rays, as through a tubular passageway for a considerable distance from the main body of the casing, directly to the body or part to be treated; to provide for universal movement or swinging of the casing 45 to project the rays in any direction required; and to provide against hot mercury falling on the patient in case of lamp breakage while in use.

An illustrative embodiment of this invention is shown in the accompanying drawings, in which—

Fig. 1 is a longitudinal axial section through the casing, positioned as in Fig. 2 for projecting rays horizontally, and showing the apparatus contained therein.

Fig. 2 is a cross-section on the line 2—2 of Fig. 1.

Fig. 3 is an end view of the device with a tubular ray conducting attachment in place, and with the casing tilted downward. 60

Fig. 4 is an end view of the device as shown in Fig. 5.

Fig. 5 is a front elevation of the device as a whole, with the shutters drawn apart to provide a horizontally facing aperture, 65 as viewed from the left of Fig. 2.

Fig. 6 is a sectional view at 6—6 on Fig. 1.

Fig. 7 is a sectional view at 7—7 on Fig. 1.

Fig. 8 is a section at 8—8 on Fig. 3, showing a reducing diaphragm or iris at the 70 outer end of the tube.

Fig. 9 is a plan of the iris diaphragm of Fig. 8.

In the construction shown in the drawings the ray generating unit or lamp 1 is 75 mounted in a casing 2, which in turn is supported by an arm or bracket 3, which bracket is normally secured to an adjustable support 4, preferably mounted slidably on an upright frame 5 or the like, as shown 80 in Fig. 4.

The casing 2, as a whole, when closed is cylindrical in shape with closed ends 6 and 6' connected rigidly by a half cylindrical wall member 7 and a pair of quadrant members 8 in the form of arcuate shutters, having segmental ends 9 mounted to swing concentrically about the main axis of the casing on pivots 10 and 10' carried by the 85 bracket 3.

The mercury vapor lamp 1 is carried directly by a tiltably mounted frame 11 pivotally supported at 12 on the U-shaped axially mounted bracket 13, and said frame is provided with tilting means for starting 95 the lamp, as hereinafter described.

One end of bracket 13 is ring-shaped and receives the inner end of the pivot 10' in tight-fitting relation and is rigidly fastened thereto, as by means of a set screw 14. The 100 other end of said bracket is provided with an integrally formed barrel member 15 projecting axially outward into the hollow pivot 10 to which it is turnably related.

The pivot 10 is cup-shaped with a knob 105 or handle 16 secured to its outer end and with an outwardly disposed radial flange 17 at its inner end to which the casing wall 6, reinforced at this point by ring 6'', is secured rigidly as by means of screws 18. A 110

stop ring 19 is provided on said pivot and secured thereto by said screw 20, between which ring and the flange 17 is disposed the perforated inner end of the bracket 3 together with a plurality of spacing washers 21 to provide clearance for the relatively movable radially disposed parts, as will be understood.

The handle 16, pivot 10, and main casing members 6, 6' and 7 carried thereby, are normally held in rigid non-turning relation to the bracket 13 by means of a manually operable lock 22, the opposite end of bracket 13 being rigid with the main supporting bracket 3, as will be more fully explained.

The lock 22 is T-shaped and includes an axially disposed body part or bar 22' slideable lengthwise in the handle 16 and in the adjacent bracket end 15 in non-turning relation to the handle 16 and pivot 10, being rectangular in section to fit the correspondingly shaped hole 23 in said pivot. The inner end of said bar fits turnably relative to the hollow bracket head 15, but is normally prevented from turning therein by means of the T-lock cross-head 24 fixed to the shank 22', said cross-head having inwardly turned tips 24' to engage the circularly disposed series of depressions 25 in the bracket part 15.

The helical compression spring 26 is mounted in the chamber 27, provided by the hollow head 15 and pivot 10 and is disposed to bear at one end against the inner end wall 35 of said chamber and at the opposite end against a shoulder 28 on the middle part of said bar 22' whereby the lock is urged outward to hold the T members in its effective non-turning position, though the locking tips 24' may be released from bracket 13 by inward pressure of the hand on the handle 29 on the outward tip of said bar 22'.

The lock 22 is provided with a centering pin 30 integral with bar 22 and projecting 45 through the part 24 and into the centrally apertured bearing cap 31 fixed on the inner end of the bracket head 15.

The pivot 10' at the opposite end of bracket 13 comprises a hollow metallic casting 32 with a core 33 preferably of insulating material, the casing 32 being held rigid with bracket 13 as above indicated. Said pivot 10' is perforated endwise and contains a manually operable crank-shaft 34 extending therethrough and journaled therein. The outer end of said crank-shaft is provided with a handle 35 and the inner end has a crank arm 36 for tilting the lamp 1, as will be described.

Said pivot 10' on its outer end is provided with a rigid plate 37 on which is mounted a switch member 38 having a pair of contacts 39. A pair of insulated conductors 40 extend from said contacts 39 through said plate 38, thence inward through an aperture

41 in said pivot and thence to a pair of insulated terminals 42 and 43 respectively, fixed on the bracket 13. The electrical contacts on the ends of the lamp 1 are connected to said terminals by means of flexible bead 70 insulated conductors 44 and 45 respectively.

In order that the lamp 1 may be suitably tilted for starting, the frame 11 is provided with an arm 46 coacting loosely with the free end of the above-mentioned crank arm 36, the operating parts being so related mechanically that turning of the handle 35 serves to lift the arm 46 and so tilts the lamp to its starting position, and the pivot 12 being so positioned relative to the mass of the lamp and tilting mechanism that gravity will restore the lamp to its normal operating position as soon as the handle 35 is released. The frame 11 is substantially U-shaped, with detachable arms 47 and 47' adapted 85 for the particular form of lamp or tube used. The outer ends of the arms are apertured to receive the corresponding ends of the vapor tube. Arm 47 has a perforation 48 and the other arm 47' has a socket 49 provided with a detachable fastening 50 to grip the upturned tip of the mercury holding lower end of the tube.

In order to increase the efficiency of the lamp and help direct the rays in the desired 95 direction, a reflector 51 is mounted centrally on the bracket 13 in adjustable circular relation to the lamp. The reflector is of arcuate shape and of semi-cylindrical character. It is carried directly by an outer concentric 100 member 52 spaced somewhat therefrom, except at the edges where it is held by fastenings 52'. Said member 52 is provided with a slot 52'' extending circumferentially to receive the headed end of a supporting lug 105 53, mounted on the rigid upstanding arm 54, which in turn is secured by screws 55 to the bracket 13. Said reflector is thus adapted to be oscillated through a vertical angle of nearly 180°, whereby it may be 110 manually adjusted from time to time to throw the rays in whatever direction may be required, as for instance, upward, horizontally or downward.

The main casing segment or half cylinder 115 7 is of double walled character and is provided with a central slot or ventilating aperture 56 extending from end to end. On each side of the draft vent 56 the casing comprises an outer wall 57 and an inner 120 wall 58 with an air space 59 between. The outer wall 57 is provided with a circumferential slot 60 to receive an adjustable fastening 61 for the shutters 8, as hereinafter described.

Each casing quadrant or shutter 8 is also 125 of double wall construction with an air space 62 between the outer wall 63 and the inner wall 64. Said outer wall is provided with a series of ventilation apertures 65 adjacent to its edge 66 which is nearest the main 130

light aperture 67 when the shutters are opened. The inner wall 64 is also provided with a series of apertures 68 disposed remotely from said edge 66 so that in operation 5 a draft passage is provided extending inward through the apertures 65, through the chamber 62 and thence through apertures 68 into the open interior of the casing past the lamp 1 and out at the slot 56.

10 Each shutter 8 is provided preferably near its center with apertures 69 adapted, for instance, to facilitate inspecting the lamp when in use. Each aperture 69 is provided with a short radially disposed sleeve or tube 15 70 held in place by a flange 71 at its inner end. The outer end of said tube may be provided with a lens or ray filter 72 secured in place by an inwardly flanged ring 73, as shown at the top of Fig. 2. If desired, the 20 opposite tubular aperture may be provided simply with a closed cup 74, as shown in the lower side of Fig. 2, or, if desired, a tubular extension 75 may be substituted in place of the cup, as illustrated in Fig. 8. It is to 25 be understood that the several cups or tubular extensions are provided with a readily detachable connection or fastening, as for instance, a bayonet notch 67 illustrated in Figs. 3 and 8. If desired, a restricted opening 30 may be provided at the outer end of tube 75 as by means of an interchangeable washer-like member or iris 77. It is to be understood also that if desired, a concentrating lens may be used in place of said member 77 35 and held in substantially the same manner as shown at the top of Fig. 2. The members 72 and 74 are readily attachable and removable interchangeably by means of fastenings 76', as for instance bayonet catches.

40 In order to lock the shutters positively in the desired position respectively, relative to the main casing 7, the said lock 61 is provided with outwardly turned teeth 78 on the cross-head 79 of the lock plunger 80. The 45 outer end of said plunger is provided with a handle 81 to receive the pressure of the hand for forcing the lock inward against the force of the compression spring 82 to release said teeth from the notches 83, which are disposed 50 in the outer casing wall 57 adjacent to the slot 60. The guide-block 84 is fixed on the outer side of the shutter adjacent to its edge 55 to support the outer part of lock 61 and house the spring 82, and to serve also as a handle for oscillating the shutter.

It is to be understood that the main supporting bracket 3, though here shown as mounted horizontally, may be arranged vertically so as to swing freely from above, if 60 desired, though in any case the bracket 13 which is rigid therewith is preferably arranged to be held in a horizontal position, as shown in Fig. 2.

In order to provide efficiently for an intense diffused light the interior walls of the

casing as a whole are coated with a thin vitreous white enamel which is a non-absorbent for therapeutic rays. The active surface of the reflector 51 is likewise glazed or enameled.

Safety against burning the patient by 70 hot mercury in case of lamp breakage is assured by normally inclining the appliance so that the lower shutter is always disposed as a receptacle to catch any falling mercury. In this connection see Figs. 2, 3, 4 and 5. 75

The operation of the device is as follows: Referring first to Figs. 3 and 4, the casing is brought to the proper height and swung horizontally to the proper position relative to the patient as provided for by the counter-weight 86 and cord 87 connecting same to the rotatably mounted sleeve 4 carried by the hollow post 5. The reflector 51 is adjusted to throw the light in the direction required. The main casing member is then 80 oscillated by due manipulation of the handle 16 and lock 22 to bring the main ray aperture 67 to the required position. The amplitude of the opening 67 is then adjusted by manipulating the handles 84 and latch 90 means 61, whereby the shutters are adjusted. If only a small beam of rays is required, as for limited local treatments, the shutters may be entirely closed and the casing swung to such a position that one of 95 the apertures 69 or a tube 75 may be used. The ray generator or lamp is then started by twisting or tilting the handle 35, which operates to lift the large end of the lamp sufficiently to cause the mercury to flow 100 momentarily to the opposite end and so start the arc, whereupon it returns by gravity to its normal position upon releasing the handle 35. The operation of the lamp may be observed through the colored glass 105 window 72. The strength of the rays at any time may be ascertained sufficiently for all practical purposes, after a little experience, by holding the hand for a brief period in the direct path of the rays and then noting the slight burning odor which is readily perceptible, upon raising the hand to the nose, the degree of such odor being a measure of the effectiveness of the 110 lamp.

Although but one specific embodiment of this invention has been herein shown and described, it will be understood that numerous details of the construction shown may be altered or omitted without departing 120 from the spirit of this invention as defined by the following claims.

I claim:

1. A radio-therapeutic device adapted for generating and applying light therapy 125 rays, comprising a supporting bracket, an open-sided casing member mounted pivotally thereon, a lamp also mounted on said bracket within said casing member but independent mechanically of the latter, clo- 130

sure means operatively related to said member adapted for adjusting the degree of opening, and means to variably adjust the relative position of said member and 5 bracket, said bracket including a pair of arms having pivotal bearings disposed in horizontal alinement, and said casing member and closure means as a whole being of cylindrical shape and mounted to turn on 10 its main axis.

2. A radio-therapeutic device comprising a casing provided with closed ends and a cylindrical wall of sectional character including a main wall part and arcuate 15 shutters movable concentrically therewith to provide an adjustable ray aperture, and a ray generating unit mounted axially in said casing.

3. A radio-therapeutic appliance comprising a mercury vapor lamp, a casing therefor having a ray aperture, and a support whereon said casing and lamp are independently mounted, said casing being 20 tilttable to direct the rays as may be required and said lamp being tilttable for starting, said casing also having manually 25 adjustable means for setting the position of the casing relative to said support, and said lamp having a flexibly connected handle extending through said casing for tilting the lamp.

4. A radio-therapeutic device comprising a vapor lamp, a casing therefor having a limited ray aperture, a reflector arranged to 35 deflect the rays through said aperture, and a tubular ray conduit having a vitreous lining adapted for insertion into a speculum to apply the rays directly to an interior part of the anatomy to be treated.

40 5. A radio-therapeutic device comprising a cylindrical casing, a support whereon said casing is rotatably mounted on its main axis and a lamp also mounted on said support independently of said casing though con-

tained therein, said casing including a main 45 body part of semi-cylindrical shape and a pair of quadrant shutters adapted to more or less close the open side of said main part, each of said casing members being provided with ventilating means extending lengthwise along a medial line thereof. 50

6. An air cooled universal control therapy lamp comprising in combination a tiltably mounted and adjustably apertured casing, a quartz bulb mercury-arc ray generator independently tilttable therein for starting, and an adjustable reflector therefor, said casing having draft apertures to facilitate and insure adequate ventilation and cooling of the generator. 60

7. A therapy lamp casing of substantially cylindrical shape provided with a side opening and an adjustable axially mounted concentric shutter to open or close said opening, said shutter being arranged to pass 65 over the adjacent casing wall in opening and being provided with a radially acting manual latch to engage the casing for securing the shutter in any desired position.

8. A therapy lamp casing of substantially 70 cylindrical shape provided with a side opening and an adjustable axially mounted concentric shutter to open or close said opening, said shutter being arranged to pass over the adjacent casing wall in opening 75 and being provided with a radially acting plunger latch having an inner cross-head with an outwardly turned catch part, and said casing having an arcuate slot to receive said latch, and yielding means urging 80 said latch outwardly to engage said casing, the latter being formed and adapted to be engaged positively by said catch part.

Signed at Chicago this 7th day of April, 1920.

FRED F. BURDICK.
FRITZ ARTHUR ANDERSON.
